MEN'S UNDERGARMENTS

Nels A. Severson, Minneapolis, Minn., assignor to Munsingwear, Inc., Minneapolis, Minn., a corporation of Delaware

Application January 18, 1957, Serial No. 635,069

5 Claims. (Cl. 128—159)

This invention relates to new and useful improvements in men's undergarments of the general class disclosed in Patent No. 2,310,839 granted to Franklin Chatfield et al., February 9, 1943.

The garment disclosed in the above mentioned patent has been very popular in the trade over a period of years. While it has proven extremely practical and efficient in general use, it has one weakness which the present invention aims to correct. This weakness resides in the manner in which the rear end portion of the crotch member is secured in the seat portion of the garment. In the garment disclosed in the above noted patent, a segment shaped opening is provided in the seat portion of the main body blank to receive the segment shaped rear end portion of the crotch member. When thus constructed, the crotch blank is secured to the main body blank by a plurality of seams, which obviously increases the manufacturing cost. Moreover, by utilizing a plurality of seams in the seat portion of the garment, as above stated, the seat portion of the garment may be weakened to the extent that tensional strains imposed therein as a result of stooping or bending body movements, may cause the fabric to tear or rip along the rear transverse seam of the crotch member, and thereby destroy the usefulness of the garment.

An important object in the present invention, therefore, is to provide a man's undergarment comprising a uniquely shaped crotch member whose rear end portion is substantially circular in configuration and is adapted to be fitted into an enlarged circular opening in the seat portion of the garment blank, whereby the rear end portion of the crotch member may be secured to the seat portion of the garment by a continuous unbroken seam extending around the entire rear end portion of the crotch member, whereby tensional strains exerted in the seat portion of the garment are distributed over a relatively wide area of the seat of the garment, thereby greatly strengthening the connection between the rear end portion of the crotch member and the seat of the garment, whereby the fabric and stitching are not likely to tear, even when the fabric of the seat portion of the garment is subjected to severe tensional strains.

A further object of the invention resides in the specific formation of the crotch blank and the contour of the opening provided in the seat portion of the body blank, whereby the crotch member may be stitched to the body blank by a continuous unbroken seam extending from the waist band downwardly along one side of the front of the crotch member, and rearwardly around the rear circular end portion of the crotch member, thence forwardly and up the other side of the front end of the crotch member to the waist band, thereby greatly facilitating the operation of securing the crotch member to the body of the garment.

These and other objects of the invention and the means for their attainment will be more apparent from the following description taken in connection with the accompanying drawings.

2

In the drawings there has been disclosed a structure designed to carry out the various objects of the invention, but it is to be understood that the invention is not confined to the exact features shown, as various changes 5 may be made within the scope of the claims which follow.

In the drawings:

Figure 1 is a rear view of a garment showing the invention embodied in the seat portion thereof;

Figure 2 is a front view of the garment positioned on 10 a body;

Figure 3 is a rear view of Figure 2;

Figure 4 is a view showing the blank from which the main body portion of the garment is constructed, including the leg portions thereof;

15 Figure 5 is a view showing the blank from which the crotch member is constructed; and,

Figure 6 is a view showing the blank from which the front wall of the garment is constructed.

The garment herein described is shown comprising a 20 main body portion 2 having leg portions 3—3, and a crotch member, generally designated by the numeral 4, as shown in Figures 1, 2 and 3. The main body portion 2 of the garment may be constructed of one or more blanks, or of tubular knit fabric, as may be desired. In 25 the present instance the body of the garment is shown made from a main body blank 5, shown in Figure 4, a front panel or wall section 6, shown in Figure 6, and a crotch blank 7, shown in Figure 5.

The main body blank 5 is shown provided with leg 30 portions 8—8, separated by an elongated opening 9, extending upwardly from the bottom edge 11 of the blank.

An important feature of the present invention resides in the unique construction of the rear end portion of the 35 crotch member and the manner in which it is secured to the seat portion of the garment body whereby tensional strains imposed in the seat portion of the garment and the rear end portion of the crotch member are distributed over a relatively wide area of the rear portion of the

40 garment body, whereby the stitching securing the rear end portion of the crotch member to the seat portion of the garment is not likely to become damaged from such strains, and whereby the seam will last the life of the garment.

45 To thus distribute the tensional strains over a relatively wide area of the seat portion of the garment, the rear central or seat portion of the garment blank is provided with an enlarged opening 13 which is substantially circular in shape, as shown, and has its lower portion in communication with the upper end of the elongated upright opening 9, as clearly illustrated in Figure 4. The leg portions of the garment are defined by the edge portions 11, 14 and 15 in a manner similar to the garment disclosed in the hereinbefore mentioned patent.

50 The crotch blank 7, as best illustrated in Figure 5 is shown provided with oppositely extending wings 16—16 the lower edges 17—17 of which are adapted to be stitched together by a seam 18 as shown in Figure 2, thereby to provide a fullness in the front portion of the 55 crotch member to serve as a suspensory.

The specific construction of the front or wing portion of the crotch member and the manner in which it is secured to the front portion of the garment body, is shown and described in detail in Patent #2,328,953, granted to Franklin Chatfield and Jennie M. Lindh on September 7, 1943, and forms no part of the present invention.

55 The distinguishing feature of the present invention over 70 the garment shown in the above mentioned patent resides principally in the design of the rear end portion of the crotch member and the method in which it is secured

to the seat portion of the garment body, as hereinbefore stated.

As best illustrated in Figure 5 the rear end portion 12 of the blank is circular in configuration and is adapted to be fitted into the enlarged circular opening 13 in the body blank 5, with its circular edge 19 coinciding substantially with the circular edge 21 defining the opening 13 in the body blank 5. Edges 19 and 21 are secured together by a circular seam 22 which extends around the rear circular end portion of the crotch member and forwardly through the groins, as illustrated in Figure 1, and thence continues upwardly to the waist band 23 of the garment, by seams 24-24. The upright seams 24 thus secure the upright edges of the front end portion of the crotch member to the body of the garment, and simultaneously secures the front wall panel 6 in position between the side wall sections 25 of the garment body, as will be understood by reference to Figure 2.

It will thus be seen that by enlarging the rear end portion of the crotch blank 4 and making such end portion substantially circular in configuration, when the rear end portion of the crotch member is fitted into the enlarged circular opening 13 in the body blank and its marginal edge 19 is stitched to the marginal edge 21 of the body blank, the tensional strains imposed in the seam 22 will be distributed over a relatively wide area of the seat portion of the garment. Seam 22 will also be void of sharp corners or angles, whereby maximum strength is assured. Before stitching the crotch member in position in the body blank the edge portion 17-17 of the crotch blank is stitched together by the seam 18, as hereinbefore stated, whereby the upright side edges of the front end portion of the crotch member are brought into substantially parallel relation so that the crotch member may be secured in position in the garment by a single seam, indicated by the numerals 22 and 24-24.

By constructing the crotch member 4, as herein disclosed, and securing it to the seat portion of the garment in the manner described, the operation of securing the crotch member in position in the garment is greatly facilitated and, in addition, the tensional strains exerted in the fabric, particularly in and about the seam 22, are distributed over a relatively wide area, whereby the fabric is not likely to tear or become weakened along the seam 22, as a result of bending or stooping movements by the wearer. To enable the rear end portion 12 of the crotch member to stretch freely in an up-and-down direction, when the seat of the garment is subjected to tensional strains, the wales of the fabric in the rear end portion 12 of the crotch blank 7 are disposed horizontally, as indicated by the arrow 20, in Figure 5, whereby the rear portion of the crotch member may freely stretch in an up-and-down direction, as indicated by the arrow 30 in Figure 1, thereby to relieve the fabric from severe tensional strains.

From the foregoing, it would be noted that the seam 22-24 may be completed in a single operation without interruption, and because of the rear circular end portion 12 of the crotch member constituting a relatively large portion of the seat of the garment, tensional strains imposed to the fabric will be distributed over a relatively greater area of the seat and back portion of the garment body, whereby the rear portion of the garment including

the seam 22 will withstand normal wear throughout the life of the garment.

The foregoing detailed description has been given for clearness of understanding only, and no unnecessary limitations should be understood therefrom, and the appended claims should be construed as broadly as permissible in view of the prior art.

I claim as my invention:

1. In a garment of the class described, a body portion comprising back and side walls, said side walls extending around the sides to the front of the garment and having their upright edges at the front of the garment spaced apart laterally, a front wall section fitting between said upright side wall edges and having its lower horizontal edge terminating above the crotch portion of the garment, the lower central portion of said back wall having an enlarged circular opening therein, a crotch member having an enlarged circular rear end portion fitting in said opening and having its opposite end portion extending forwardly and upwardly and overlying the lower portion of said front wall section with its vertical side edges coincident with the vertical edges of said side walls, and a continuous unbroken seam securing the marginal side and rear edges of the crotch member to the body of the garment, the lower marginal edge of said front wall section and the upper marginal edge of the crotch member being free and unattached and cooperating to provide a normally closed fly opening.

2. A garment according to claim 1, wherein the vertical edges of the front wall section and said crotch member are secured to the body portion of the garment by a single unbroken seam.

3. A garment according to claim 1, wherein the crotch member, prior to being secured in the garment, is provided with means for providing a fullness in the lower forward portion thereof, when the crotch member is subsequently secured in position in the garment.

4. A main body blank for a garment having an enlarged circular opening in the lower central portion of the seat forming portion thereof, said blank also having an elongated opening therein extending downwardly from the circular opening in the blank to the lower edge thereof, said openings facilitating the formation of the leg portions of the garment and the operation of securing the crotch member therein.

5. A main body blank for a garment comprising leg forming portions and having an enlarged circular opening in the central portion thereof extending well up into the seat forming portion of the blank, and a vertically disposed opening located in the vertical axis of the blank and communicating at its upper end with said enlarged circular opening, and extending downwardly therefrom to the lower edge of the blank, said enlarged circular opening and said vertically disposed opening facilitating the subsequent completion of the leg portions of the garment and the operation of securing the crotch member in position in the garment.
